[57] CLAIM

The ornamental design for a portable grill, as shown.

DESCRIPTION

FIG. 1 is a front perspective view of the portable grill, with the cover closed and with the handle lowered; FIG. 2 is a front elevation thereof with the handle raised;

FIG. 3 is a side elevation thereof, with the handle raised;

FIG. 4 is a rear elevation thereof, with the handle raised;

FIG. 5 is a front perspective view of the portable grill of FIG. 1, but with the cover open and with the handle lowered.
